CLAIM

The ornamental design for a calculator case, as shown and described.

DESCRIPTION

FIG. 1 is a perspective view of a calculator case showing our new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a rear elevational view thereof;

FIG. 7 is a bottom plan view thereof.

Fig.2.

Fig.3.

Fig. 7.

Fig. 6.

UNITED STATES PATENT AND TRADEMARK OFFICE
CERTIFICATE OF CORRECTION

PATENT NO. : Des. 308,986

Page 1 of 6

DATED : July 3, 1990

INVENTOR(S) : Sereika et al

It is certified that error appears in the above-identified patent and that said Letters Patent is hereby corrected as shown below:

The title page showing the illustrative figure should be deleted to appear as per attached title page.

The three (3) sheets of drawings should be deleted to be replaced with the four (4) sheets as shown.

Signed and Sealed this

Eighteenth Day of June, 1991

Attest:

HARRY F. MANBECK, JR.

Attesting Officer

Commissioner of Patents and Trademarks
